(57) **CLAIM**

The ornamental design for a climate tower, as shown and described.

DESCRIPTION

FIG. 1 shows a left front perspective view of a climate tower in accordance with an embodiment of the present design.

FIG. 2 shows a top view of the climate tower of FIG. 1.

FIG. 3 shows a left side view of the climate tower of FIG. 1.

FIG. 4 shows a front view of the climate tower of FIG. 1; and,

FIG. 5 shows a right side view of the climate tower of FIG. 1.

The solid lines in FIGS. 1-5 illustrate a climate tower according to the present design. The broken lines in FIGS. 1 and 3-5 are for illustrative purposes only and form no part of the claimed design.

1 Claim, 5 Drawing Sheets
